RUTH H. USHER, OF BROOKLYN, NEW YORK.

DESIGN FOR A DOLL.

57,025.

Specification for Design. Patented Jan. 25, 1921.

Application filed July 1, 1920. Serial No. 393,419. Term of patent 3½ years.

To all whom it may concern:

Be it known that I, RUTH H. USHER, a citizen of Great Britain, residing at Brooklyn, in the county of Kings and State of New York, have invented a new, original, and ornamental Design for a Doll, of which the following is a specification, reference being had to the accompanying drawing, forming part thereof in which:

Fig. 2 is a rear view of the same.

Fig. 3 is a side view thereof.

I claim:

The ornamental design for a doll, substantially as shown.

RUTH H. USHER.
